FIG. 1 is an isometric view of first embodiment of a funnel according to my new design.

FIG. 2 is a top view of the design for a funnel shown in FIG. 1;

FIG. 3 is a bottom view of the design for a funnel shown in FIG. 1;

FIG. 4 is a rear view of the design for a funnel shown in FIG. 1;

FIG. 5 is a front view of the design for a funnel shown in FIG. 1;

FIG. 6 is a right side view of the design for a funnel shown in FIG. 1, the left side view being a mirror image thereof;

FIG. 7 is an isometric view of a second embodiment of a funnel according to my new design.

FIG. 8 is a top view of the design for a funnel shown in FIG. 7;

FIG. 9 is a bottom view of the design for a funnel shown in FIG. 7;

FIG. 10 is a rear view of the design for a funnel shown in FIG. 7;

FIG. 11 is a front view of the design for a funnel shown in FIG. 7; and,

FIG. 12 is a right side view of the design for a funnel shown in FIG. 7, the left side view being a mirror image thereof. The broken lines depict portions of the funnel that form no part of the claimed design.
